CLAIM

The ornamental design for a universal glove dispenser, as shown and described.

DESCRIPTION

FIG. 1 is a top, right and back perspective view of a universal glove dispenser, showing the novel design; FIG. 2 is a right side elevational view thereof; FIG. 3 is a left side elevational view thereof; FIG. 4 is a back side elevational view thereof; FIG. 5 is a front side elevational view thereof; FIG. 6 is a top plan view thereof; and, FIG. 7 is a bottom plan view thereof.

The broken lines depicted in any of the FIGS. 1-7 are perforations visible on surfaces of the universal glove dispenser and the broken lines form part of the claimed design.

1 Claim, 7 Drawing Sheets(56)
